UNITED STATES PATENT OFFICE

168,210

BROOCH OR THE LIKE

William C. Bundy, Los Angeles, Calif.

Application May 6, 1952, Serial No. 19,616

Term of patent 3½ years

(Cl. D45—19)

To all whom it may concern:

Be it known that I, William C. Bundy, a citizen of the United States, residing in the city of Los Angeles, county of Los Angeles, and State of California, have invented a new, original, and ornamental Design for a Brooch or the like, of which the following is a specification, reference being had to the accompanying drawings, forming a part thereof.

Fig. 1 is a front elevational view of a brooch showing my new design; Fig. 2 is a side elevational view thereof; and Fig. 3 is a rear elevational view thereof.

The dominant features of my design reside in those portions shown in full lines.

I claim:

The ornamental design for a brooch or the like, as shown and described.

WILLIAM C. BUNDY.
